DESIGN FOR A TOOL CABINET

Albert P. Siersma, Chicago, Ill., assignor to Snap-On Tools Corporation, Kenosha, Wis., a corporation of Delaware

Application May 18, 1940, Serial No. 92,460

Term of patent 7 years

To all whom it may concern:

Be it known that I, Albert P. Siersma, a citizen of the United States and a resident of Chicago, county of Cook, and State of Illinois, have invented a new, original, and ornamental Design for a Tool Cabinet, of which the following is a specification, reference being had to the accompanying drawing, forming part thereof.

In the drawing:

Figure 1 is a front view in elevation of a tool cabinet showing my new design.

Figure 2 is a side view in elevation thereof.

Figure 3 is a front view in elevation of the tool cabinet shown in Figure 1 with the front flexible panel drawn up to enable access to the drawers and the lamp support is in raised position.

Figure 4 is a plan view thereof.

The rear panel of the tool cabinet is plain.

I claim:

The ornamental design for a tool cabinet, substantially as shown and described.

ALBERT P. SIERSMA.
